UNITED STATES PATENT OFFICE.

RAY L. STOKELY, OF FLORAL PARK, NEW YORK, ASSIGNOR TO WESTERN ELECTRIC COMPANY, INCORPORATED, OF NEW YORK, N. Y., A CORPORATION OF NEW YORK.

TOLL TRUNKING CIRCUITS FOR MACHINE-SWITCHING TELEPHONE SYSTEMS.

Application filed March 1, 1921. Serial No. 448,890.

To all whom it may concern:

Be it known that I, RAY L. STOKELY, a citizen of the United States, residing at Floral Park, Long Island, in the county of Nassau and State of New York, have invented 5 certain new and useful Improvements in Toll Trunking Circuits for Machine-Switching Telephone Systems, of which the following is a full, clear, concise, and exact description.

This invention relates to machine switching telephone exchange systems wherein the substation lines are provided with coin boxes, and wherein it is necessary to collect or refund deposited coins over toll switching 15 trunks from a toll operator's position. It is an improvement upon the system shown and described in my application for machine switching telephone exchange systems, Serial No. 412,795 filed September 25, 1920. In the system disclosed in that application, special coin collect trunks must be provided from the toll position to the different automatic offices having coin lines, and the number of 20 the particular toll switching trunk used by the toll operator in extending the connection to the automatic office is dialed over one of such special trunks; that is to say, the toll operator after having built up the connection over the conversational toll switching 25 trunks, plugs into the jack of one of these special trunks leading to the distant automatic office through which the connection to the calling line extends, this trunk terminating in a special connector at such automatic office. The toll operator by means of 30 the dial in her special cord circuit then sets such connector upon multiples of the used toll switching trunk in the automatic office. 35 She can then by means of collect and refund keys in such cord circuit impress current on the toll switching trunks and thence to the calling line to operate the polarized magnet in the coin box to collect or refund the deposited coins.

In the present arrangement the relays at the automatic office which apply the coin current to the substation line are operated from the toll position directly over the two-wire 50 interoffice conversational toll switching trunk itself, thus eliminating the special coin collect trunks and the special connectors referred to, and also eliminating the extra dialing operation of the toll operator to set the special connectors.

A further feature of this invention is an arrangement for transmitting a tone from the automatic office from which the current for operating the coin boxes is applied, back to the toll operator's head set to inform her that 60 the coin collect or coin refund circuit, as the case may be, is functioning properly.

Referring to the drawings, Fig. 1 shows a toll cord circuit; Fig. 2 shows a trunk circuit outgoing from the toll board to the full 65 mechanical or automatic office; Fig. 3 shows an incoming selector thereat; Fig. 4 shows the relay and repeating coil equipment associated with the toll transmission selector, which selector is also shown on this sheet; 70 Fig. 5 shows a combination toll and local connector circuit.

Referring first to Fig. 1, this drawing shows a cord circuit at the toll operator's position. The left-hand side of this circuit 75 will be called the toll end and the right-hand side will be called the toll and trunk end. In general, the operation is as follows: The operator answers an incoming call by inserting the plug T of 80 the toll end in the answering jack J. If the called subscriber is located in a nearby automatic exchange, the call is completed by inserting the plug TT of the trunk and toll end in a toll switching trunk 85 jack TSJ. The operator then actuates the dialing and monitoring key DK which causes the relay B-34 to operate, which in operating energizes a monitoring relay (not shown) to place the operator's telephone set 90 O. T. in a monitoring position on the cord. The operator now turns the dial D for the first digit of the wanted number. The dial in moving out of its normal position short circuits the relay B-34 permitting the relay E-72 to operate. Relay E-72 in operating locks itself to battery and transfers the tip of the plug TT through the impulse springs 108 of the dial D to the battery. The dial, in returning to normal, interrupts 95 the battery to the tip of the plug causing the impulse relay A-2 of the trunk circuit of Fig. 2 to operate intermittently, the number of times depending upon the digit involved. This impulse relay, in thus operating, causes the setting of the incoming selector (Fig. 3) at the distant automatic office which thereupon automatically finds an idle trunk in the selected level. This trunk 100 includes the equipment shown in Fig. 4 and 105 110

- terminates in the toll transmission selector shown in that figure. When the operator has turned the dial for all of the digits involved causing the last switch or connector 5 (Fig. 5) to be set on the desired line, she restores the monitoring DK. If the called line is not busy the trunk and toll supervisory lamp 100 lights as a ringing signal, whereupon the operator by depressing ringing key 10 RK causes the connector to start the ringing of the called line, which ringing continues until the called party answers, whereupon the ringing current is cut off and the lamp 100 is extinguished. When the 15 called subscriber replaces his receiver, this lamp again lights as a disconnect signal.
- If the called line is busy or if one of the 20 selectors fails to find an idle trunk, the lamp 100 will flash, the frequency of the flashes depending upon the busy condition encountered. The toll operator in response to the 25 flashing of the lamp removes the plug TT of the trunk and toll end of the cord from the toll switching jack TSJ, but before removing the toll plug T from jack J, the operator by means of her ringing key R' K', rings on the toll line terminating at the jack J to notify the distant originating operator that the line is clear. If the distant originating operator rings first, however, the toll 30 supervisory lamp 101 lights and when the operator actuates listening key LK, or pulls out the plug T, this lamp is extinguished.
- If the call is for a subscriber who can be 35 reached only over a toll line terminating at a toll position at a distant terminating office, the toll operator who answers the originating operator inserts the plug TT of the trunk and toll end in a toll line jack leading to 40 such distant terminating office and by means of her ringing key RK rings out over such toll line to signal the distant terminating operator who then completes the connection. When the terminating toll operator at the 45 distant end applies ringing current to the trunk at the termination of the conversation, the toll supervisory lamp 101 lights until the listening key LK is operated or the connection is taken down. The keys K and 50 K' serve, when operated, to disconnect either end of the cord circuit from the operator's telephone set when the operator is talking on the other end.
- More in detail, when the plug T of the 55 toll end is inserted in toll answering jack J, relay E-156 operates, in turn operating relay B-162. Relay B-162 opens the circuit of slow to operate relay E-162 preventing the toll supervisory lamp 101 from lighting. 60 When the plug TT of the trunk and toll end is inserted in toll switching trunk jack TSJ leading to an incoming selector at an automatic office, relay E-99 operates in series with relay E-155 and the right winding of 65 relay E-156. Relay E-99 disconnects the

busy test equipment of the operator's telephone set from the tip of the cord and connects the tip of the cord through to the ringing key. Relay E-155 is marginal and does not operate at this time on account of the 70 high resistance in the sleeve of the toll switching trunk circuit, and thus leaves the calling supervisory relay B-43 bridged across the trunk. Ringing current applied by a distant toll operator operates the alternating current relay A-196 which releases relay B-162. The latter relay in releasing lights the toll supervisory lamp 101 and operates relay E-162 in parallel with the lamp. Relay E-162 locks up under the 75 control of the listening key LK and relay E-156 so that the lamp remains lighted after the ringing ceases and the relay B-162 is re-operated through the back contact of relay A-196. The lamp 101 may be extinguished by operating the listening key LK which releases relay E-162 or by taking down the connection which releases relays E-156 and E-162. Relay E-162 is made slow in operating to guard against the 80 possibility of lamp 101 being lighted by Morse impulses. Relay A-196 may be operated for a short time by Morse impulses and release relay B-162 momentarily, but the slow operating feature of the relay 85 E-162 will give relay B-162 time to re-operate before the relay E-162 operates and locks. When the plug TT of the cord is contemporaneously inserted in a toll line 90 jack similar to jack J terminating at another toll board position, the marginal relay E-155 disconnects the calling supervisory relay B-43 from the cord circuit. If, on a through toll connection of this character the splitting key K' is operated to disconnect the trunk and toll end TT from the operator's telephone set, relay B-43 is bridged across the trunk and toll end so that it will operate when ringing current is received from the toll board position in which 95 the toll line associated with the trunk and toll end terminates and flash the lamp 100. Since the splitting key K' is actuated, relay E-196 is not operated by such current. When the splitting key K' is in its normal 105 position this bridge for relay B-43 is opened.

Referring now to Fig. 2 which represents a toll switching trunk over which a connection is extended to an automatic exchange, 110 relay C-2 operates over its right-hand winding when the operator inserts the plug TT into jack TSJ and by attracting its armature closes a loop circuit leading to the impulse relay A-3 of the incoming selector 115 Fig. 3 at such exchange. When the dialing key DK is thrown and the dial is operated, relay A-2 operates, connecting relay I-2 across the loop leading to the impulse relay A-3 of the incoming selector at the auto- 120 125 130

matic office, Fig. 3. Relay I-2 in operating causes slow relay D-2 to operate, which relay shunts the left-hand winding of relay C-2 whereupon the latter relay releases, 5 the circuit through its right-hand winding being opened when relay E-72, Fig. 1, operates as the dial is moved out of its normal position. Relay D-2 in operating operates relay E-2 which locks up to the 10 ground at the inner left contact of relay B-2, now energized. Relay E-2 at its outer left contact locks relay D-2, independently of its original energizing circuit which leads over the front contact of relay 15 I-2. The dial, in restoring, intermittently operates relays A-2 and I-2, relay A-2 intermittently opening the loop circuit to the impulse relay A-3 of the incoming selector and relay I-2 alternately opening 20 and closing a shunt path around relay D-2. If, during the operation of building up a connection, one of the selectors fails to find an idle trunk in the selected group, it opens the loop circuit including relay I-2. Relay 25 I-2 in closing its back contact permanently shunts out relay D-2. Relay D-2 in closing its right-hand contact operates relay H-2. Relay H-2 locks up and connects interrupted battery of 60 impulses per 30 minute to the winding of relay C-2 in shunt of the resistance 200. Relay B-43 in the 35 cord (Fig. 1) follows these impulses and flashes the supervisory lamp 100 to indicate to the operator the failure to find an idle trunk.

In case the called line is busy, interrupter 233 is connected in circuit to flash the lamp 100 at a different rate to indicate to the operator the busy condition of the selected line.

In case the called subscriber's line is found to be idle by the connector (Fig. 5) this condition causes the polarized relay F-2 to operate and cause lamp 100 to remain steadily 45 lighted as a ringing signal when the operator restores the key LK. Relay F-2 in operating also energizes relay G-2 which cuts the trunk through, thus disconnecting the relays C-2 and A-2 from the circuit 50 leading back to the toll operator's position.

Having described in a general manner the operation of the system, a call will now be traced in detail.

The toll operator, having been informed 55 of the number of the wanted line and assuming this line to be in a nearby automatic exchange, tests for an idle trunk by touching the tip of her plug TT to the sleeve of the jack TSJ of the toll switching trunk, 60 and if she does not receive a click in her receiver she inserts the plug TT into the toll switching trunk jack TSJ. A circuit is thereupon closed to operate relays E-99, (Fig. 1) and B-2 (Fig. 2). Relay E-99 in 65 operating disconnects the operator's busy test

circuit from the tip of the cord. Relay B-2 (Fig. 2) in operating prepares certain circuits which will be traced later. This trunk will now test busy at the other operator's positions due to battery applied 70 to the sleeve multiples by the sleeve of the plug TT. The insertion of the plug also closes the following circuit to energize relay C-2; free pole of battery, resistance 200, right-hand winding of relay C-2, conductor 201, armature 202 of relay G-2, conductor 203, ring of the jack TSJ, ring of the plug TT, normal contact of keys 181 and RK, right-hand winding of retardation coil 120, relay B-43, armature and back contact of relay E-155, which relay is not operated when the plug TT is inserted in the toll trunk switching jack leading to an automatic office but only when it is inserted 75 in a toll line leading to a position at a distant office, left-hand winding of retardation coil 120, upper normal contact of ringing key RK, armature and front contact of relay E-99, contact of key 180, conductor 121, right-hand normal contact of relay 80 E-72, conductor 103, tip of the plug TT, tip of the jack TSJ, armature 204 and back contact of relay G-2, and relay A-2 to ground. Relay A-2 is marginal and does not operate in this circuit. Relay C-2 in 85 attracting its armature closes the following circuit to operate relay A-3, Fig. 3, which is the impulse relay of the incoming selector at the automatic office shown in Fig. 3: free pole of battery, left winding of relay 90 100 A-3 (Fig. 3), conductor 300, back contact and armature 301 of relay D-3, conductor 302, conductor 203, conductor 206, outer left-hand armature and back contact of relay H-2, conductor 207, armature and front contact of relay C-2, left-hand winding of relay 95 C-2, conductors 208 and 209, inner right armature and front contact of relay B-2, conductor 210, polarized relay F-2, conductor 211, conductor 212, conductor 303, 105 armature 304 and back contact of relay D-3, conductor 305, right winding of relay A-3, conductor 306, normally closed contact of switch 307, operated on the eleventh rotary 110 step of the selector, to ground. The operator now throws the dialing and monitoring key DK, whereupon a circuit is closed to operate relay B-34, Fig. 1, which in attracting its armature causes the operator's head set to be connected across the cord. She now rotates the dial D for the first digit 115 of the wanted number. The closure of the contact 104 of the dial as the dial moves off normal, shunts the relay B-34 which shunt operates the relay E-72 and releases relay 120 B-34. Relay E-72 in attracting its left-hand armature locks itself to ground at the contact of the dialing key DK which when actuated remains in its operated position until manually released by the operator. 125 130

Relay E-72 in closing its right-hand contact connects free pole of battery through the impulse contact 108 of the dial to the tip of the plug interposing a break in the tip conductor. The interposition of this break in the tip conductor opens the circuit heretofore traced through the right-hand winding of relay C-2. Marginal relay A-2 now operates in series with the impulse contact of the dial, the circuit being as follows: free pole of battery, resistance 109, impulse contact 108, right-hand armature and front contact of relay E-72, conductor 103, tip of the plug TT, tip of the jack TSJ, armature 204 and back contact of relay G-2, conductor 213 and relay A-2 to ground. Relay A-2 in attracting its left-hand armature bridges relay I-2 across the tip and ring of the trunk in parallel with the left-hand winding of relay C-2. Relay I-2 in attracting its armature closes a circuit, to operate slow relay D-2 as follows: free pole of battery, resistance 214, conductor 215, relay D-2, conductor 216, right armature and front contact of relay I-2, conductor 217, contact 218 of relay G to ground. Relay D-2 in attracting its left armature short circuits the left-hand winding of relay C-2 which thereupon releases, thus opening one of the bridges to the impulse relay A-3 and leaving bridged across the circuit only relay I-2. This circuit may be traced as follows: free pole of battery, left winding of relay A-3, conductor 300, armature 301 and back contact of relay D-3, conductor 302, conductors 203 and 206, outer left-hand armature and back contact of relay H-2, conductor 207, conductor 208, relay I-2, left-hand armature and front contact of relay A-2, conductor 211, conductor 212, conductor 303, armature 304 and back contact of relay D-3, conductor 305, right winding of relay A-3 and upper normal contacts of switch 307 to ground. Relay D-2 at its right armature and front contact closes the following circuit to operate relay E-2: free pole of battery, relay E-2, conductor 220, right armature and front contact of relay D-2, conductor 221, conductors 282 and 228, inner left armature and front contact of relay B-2 to ground. Relay E-2 in attracting its inner right armature locks itself to grounded conductor 282. The functions of this relay will be later described.

Dial D, Fig. 1, in returning to normal, interrupts at its impulse contact 108 the circuit of the impulse relay A-2, Fig. 2, which at its left armature interrupts the circuit of the impulse relay A-3, Fig. 3, the number of times corresponding to the first digit of the wanted number. Upon each retraction of the armature of relay A-3, the following circuit is closed for the vertical magnet 310 of the first selector: grounded armature 311, and back contact of relay D-3, conductor 312, armature and back contact of relay A-3, right armature and front contact of slow relay B-3, slow relay C-3, vertical magnet 310, and free pole of battery. Relay B-3 operated when relay A-3 operated. On the first step of the selector off normal springs 313 close the following circuit for relay 314; free pole of battery, relay 314, conductor 315, off normal springs 313, conductors 316, 317, armature and front contact of relay C-3 to ground at the left armature and front contact of relay B-3. Relay 314 in attracting its right armature locks over the following circuit: free pole of battery, relay 314, conductor 315, off-normal contact 313, conductor 316, armature and back contact of rotary magnet 318, conductor 319, conductor 320, right armature and front contact of relay 314, conductor 321 to ground at the armature 311 and back contact of relay D-3. Upon the cessation of the impulses, however, relay A-3 remains energized and consequently relay C-3 which is slow to release, after an interval, 90 releases whereupon the following circuit is closed to energize the rotary magnet 318 of the selector to step the selector brushes on to the first trunk in the selected level: free pole of battery, magnet 318, conductor 322, 95 left armature and front contact of relay 314, normal contact of relay C-3, left armature and front contact of relay B-3 to ground. At the end of its stroke, the rotary magnet 318 opens the locking circuit traced for relay 314. Relay 314 in retracting its left armature opens the circuit of the rotary magnet. If the first trunk is busy, ground is present on the test multiple 323 thereof, whereby the following circuit is closed to 100 again energize relay 314; grounded multiple 323, test brush 324, conductor 325, armature 326 and back contact of relay D-3, conductors 327, 319, back contact and armature of magnet 318, conductor 316, contact 313, 110 conductor 315, relay 314 to free pole of battery. Relay 314 in attracting its right armature again locks itself through the back contact of the rotary magnet and in attracting its left armature again closes the circuit of the rotary magnet whereupon the selector brushes are stepped to the next trunk. This interaction of the relay 314 and rotary magnet is continued until an idle trunk is found which is indicated by the absence of ground on the test multiple 323 thereof. When the rotary magnet at the end of its stroke positions the brushes on an idle trunk relay 314 does not energize but relay D-3 energizes over the following circuit: free pole of battery, relay 314, conductor 315, contact 313, conductor 316, armature and back contact of rotary magnet 318, conductor 319, conductor 327, conductor 328, relay D-3, conductor 329, lower 125 130

normal contact of switch 307, conductor 330, to ground at the left armature and front contact of relay B-3. Relay 314 is marginal and does not operate in this circuit.

5 Relay D-3 in attracting its armatures 304 and 301 extends the talking conductors through to the selector brushes and cuts off impulse relay A-3.

Assume now that the selector has failed 10 to find an idle trunk. In that event on the eleventh rotary step, switch 307 operates and opens the circuit of the impulse relay A-3 which causes the selector (Fig. 3) to restore. The opening of this loop circuit 15 also causes relay I-2 to be permanently deenergized. When the operator transmits all of the digits relay A-2 remaining attracted and the relay I-2 being inert, the following short circuit is closed about 20 the slow relay D-2 to cause the same to release: free pole of battery, resistance 214, right-hand armature and front contact of relay A-2, armature and back contact of relay I-2, conductor 217, contact 218, to 25 ground. It will be understood that relay D-2 is slow to release as shown and holds up between the impulses. Relay D-2 in retracting its right armature operates relay H-2 over the following circuit: free pole 30 of battery, relay H-2, conductor 222, armature and back contact of relay D-2, conductor 220, inner right-hand armature and front contact of relay E-2 to ground on conductor 282. Relay E-2 in attracting 35 its inner left armature locks itself to grounded conductor 282 and in attracting its inner right armature connects interrupter 223 to shunt the resistance 200 to cause supervisory relay B-43 in the cord 40 circuit to flash the trunk and toll supervisory lamp 100 at the rate of 60 flashes per minute when the operator restores the key DK. This rate of flashing will indicate 45 to the operator that one of the switches has encountered a busy trunk group whereupon she will remove the plug and will then wait and set up the connection later. While the interrupting machine 223 is connected to the front contact of relay H-2 as soon 50 as relay D-2 releases, this operation is not effective to flash the lamp until the operator, after having turned the dial for the last time, releases her dialing key DK, Fig. 1. The opening of the lowermost contact 55 of this key releases relay E-72 which in retracting its right armature again closes the loop circuit including the right-hand winding of relay C-2, Fig. 2, and the relay A-2, Fig. 2 and B-43 (Fig. 1). The relay H-2 in attracting its outer left armature interposes a break in the loop circuit leading to the selector (Fig. 3) thus preventing the subsequent sets of impulses from being transmitted.

65 The seizure of the toll transmission selec-

tor, Fig. 4, causes the closure of the following circuit for impulse relay O-4, Fig. 4 of the toll transmission selectors; free pole of battery, left-hand winding of relay O-4, conductor 400, inner right armature and 70 back contact of relay F-4, conductor 402, normal contact of relay B-4, lower left-hand winding of repeating coil 404, conductor 405, multiple terminal 334, brush 333, conductor 332, armature 301 and front contact of relay D-3, conductors 302 and 203, conductor 206, outer left armature and back contact of relay H-2, conductors 207, 208, relay I-2, left-hand armature and front contact of relay A-2, conductors 211, 212, 75 80 85 90 95 100 105 110 115 120 125 130 303, armature 304 and front contact of relay D-3, conductor 352, brush 350, multiple terminal 351, upper left-hand winding of the repeating coil, conductor 406, contact of relay B-4, conductors 407, 408, 95 contact 453 of relay F-4, conductor 409 through the right winding of relay O-4 to ground at the lower normal contact of the switch Y-4 which is operated on the eleventh rotary step of the transmission selector. The impulse relay O-4 in attracting its right armature energizes slow relay Q-4. This relay in attracting its inner left armature applies a ground over the sleeve wire 410 to multiple 323 to cause this 100 trunk to test busy and to hold up the release relay D-3 of the incoming selector in the well-known manner. When the relay Q-4 operates it closes at its outer left-hand armature the following circuit for relay J-4 in the relay and repeating coil circuit; ground, outer left armature and front contact of relay Q-4, conductors 403 and 411, contact 412 of relay M-4, conductor 413, outer right-hand armature and back 105 contact of relay B-4, relay J-4 to free pole of battery.

The second operation of the dial by the operator transmits the second digit of the called line causing relay A-2 Fig. 2 to open 110 and close the loop circuit for the relay O-4, which in vibrating its right-hand armature transmits impulses over the following circuit to the vertical magnet V-4 of the toll transmission selectors, grounded right armature and back contact of relay O-4, inner armature and front contact of relay B-4, inner armature and front contact of relay Q-4, conductor 414, armature 415 and back contact of relay M-4, slow relay T-4, magnet V-4 to free pole of battery. The brushes of the toll transmission selector are thus elevated to the desired level. When the dial returns to normal and maintains the relay A-2 energized, relay Q-4 remains energized and, after a slight interval, slow relay T-4 releases. When the relay T-4 operated on the first impulse and the selector took its first step, relay S-4 operated over the following circuit: free pole of battery, 115 120 125 130

relay S-4, upper contact of off normal switch 416, armature and front contact of relay T-4, conductor 418, to ground at the left armature and back contact of relay 5 P-4. In attracting its inner armature, relay S-4 locks itself to its own inner left armature and front contact, this circuit including the armature and back contact of rotary magnet R-4. Upon the cessation of 10 the impulses and the release of the slow relay T-4, the circuit of the rotary magnet is closed as follows: free pole of battery, magnet R-4, outer left armature and front contact of relay S-4, normal contact of relay T-4, conductor 418, left armature and back contact of slow relay P-4 to ground. The rotary magnet advances the brushes onto the terminals of the first trunk and at 15 the end of its stroke opens the locking circuit of the relay S-4 which releases, opening the circuit of the rotary magnet. If the trunk is busy, relay S-4 again energizes over the following circuit: free pole of battery, relay S-4, upper contact of switch 20 416, conductor 419, armature and back contact of rotary magnet R-4, conductor 421, back contact and armature 422 of relay M-4, conductor 423, armature and back contact of relay P-4, conductor 424, test 25 brush 425 to ground on the test multiple 426. Relay S-4, in attracting its inner armature again locks and again closes the circuit of the rotary magnet which advances the brushes to the next trunk and at the end 30 of its stroke opens the locking circuit of relay S-4 which in retracting its armature opens the circuit of the rotary magnet R-4. The switch Y-4 of the toll transmission 35 selector, Fig. 4, corresponds to the switch 307 of the selector circuit, Fig. 3. Its function is to open the circuit of the impulse relay O-4 in the eleventh rotary step of the toll transmission selector, that is to say, if all the trunks in the group are busy. 40 The opening of this circuit releases the switch and causes relay I-2 Fig. 2 to become permanently inert which causes the release of slow relay D-2 and prepares a circuit for the interrupter 223 which results 45 in the flashing of the trunk and toll supervisory lamp 100 when the operator restores her dialing key as described in detail in connection with Fig. 3.

If, however, an idle trunk is found by 50 the selector (Fig. 4) relay M-4 operates over the following circuit: free pole of battery, relay S-4, upper contact of switch 416, conductor 419, armature and back contact of magnet R-4, conductors 420, 421, relay 55 M-4, upper normal contact of switch Y-4, conductor 403 to ground at the outer left armature and front contact of relay Q-4. Relay S-4 is marginal and does not operate in this circuit in series with the relay 60 M-4. Relay M-4 in attracting its armature 427 and 428 extends the talking conductors through to the talking brushes 429 and 430. The attraction of the armature 422 of relay M-4 grounds the test brush 425 and consequently test multiple 426 of the selected trunk, causing the same to test 65 busy to other selectors. The contact 431 is made before the contact 412 is broken by the armature 432 of the relay M-4. Consequently relay J-4 Fig. 4 in the relay and 70 repeating coil equipment is maintained energized over the following circuit: free pole of battery, relay J-4, outer right armature and back contact of relay B-4, conductor 413, contact 431, brush 433, multiple 434, control conductor 435, conductor 500, conductor 501, armature 502 and back contact of relay K-5, conductor 503, sleeve conductor 550, conductor 436, multiple 426, brush 425, conductor 424, outer right armature and back contact of relay P-4, conductor 423, armature 422 and front contact of relay M-4, conductor 403, to ground 75 at the outer left armature and front contact of slow relay Q-4. Thus, the circuit for relay J-4 (Fig. 4) is maintained closed as the circuit is extended from switch to switch. As will hereafter appear, relay B-4 is not operated until the desired line 80 is found idle and seized, when it reverses the direction of current flow in the circuit leading back to the toll operator's position to light the supervisory lamp 100 to indicate to her the idle condition of the line, 85 whereupon she will cause the connector to begin the ringing operation. The switch of Fig. 5 to which the connection has been 90 extended is a combination toll and local connector containing multiples of ordinary lines in its bank. This switch is accessible not only to the toll transmission selectors of Fig. 4, but also to the local selectors which are 95 used by the subscribers in building up their own local connections. The seizure of the 100 connector causes the closing of the following circuit for the impulse relay A-5: free pole of battery, upper winding of relay A-5, conductor 504, conductor 505, left winding of slow relay J-5, conductors 506 and 507, lowermost armature and back contact of relay K-5, ring conductor 546, conductor 437, multiple 438, brush 430, conductor 439, armature 428 and front contact 105 of relay M-4, left armature and front contact of relay O-4, lower armatures and back contacts of relays L-4 and K-4, lower right-hand winding of the repeating coil 404, resistance 440, inner left armature and front contact of relay J-4, resistance 110 441, resistance 442, upper right hand winding of repeating coil 404, upper armatures and back contacts of relays K-4 and L-4, armature 427, and front contact of relay M-4, brush 429, multiple 442, tip conductor 115 443, conductor 510, upper armature and back 120 125 130

contact of relay K-5, conductor 511, conductor 512, lower winding of relay A-5 to ground. Relays J-5 and A-5 operate in this circuit, the former at its innermost right armature closing a locking circuit for itself as follows: free pole of battery, right winding and right innermost armature and front contact of J-5, conductor 514, conductor 531, conductor 515 to ground at the 5 armature 516, and front contact of slow relay B-5 which is energized upon the energization of the impulse relay A-5. Relay B-5 grounds the sleeve wire 517, leading to the test multiples in the local selectors, 10 this circuit leading from grounded armature 516, conductor 515, to conductor 517. The return of the dial to normal in the operation of transmitting the tens digit of the wanted number interrupts the circuit 15 of relay A-2, Fig. 2 which in turn interrupts the circuit of the impulse relay A-5, Fig. 5 which in vibrating its armatures transmits impulses to the vertical magnet 518 of the connector over the following 20 circuit: free pole of battery, magnet 518, slow relay 519, right contact of off normal switch 520, conductor 521, lower armature and front contact of relay B-5 to ground at the armature and back contact of the impulse relay A-5. At the first step of the 25 connector, the off normal springs 520 are shifted and the succeeding impulses are transmitted by way of the upper armature and front contact of relay 519 and the 30 contact 522 now closed at the off normal springs 520. The connector brushes are thus lifted to the desired level and upon the cessation of the impulses, impulse relay A-5 remains energized and relay 519 in 35 series with the vertical magnet releases preparing the circuit of the rotary magnet 523. The units impulses pass through the back contact of the impulse relay A-5, lower armature and front contact of relay B-5, 40 conductor 521, off normal contact 522, back contact of slow relay 519, conductor 524, left armature and back contact of relay G-5, conductor 525, uppermost armature and back contact of relay 45 H-5, rotary magnet 523 to free pole of battery. The connector is thus stepped around into engagement with the desired line. 50 If this line is idle, full potential is present on its test multiple 526 through the cut off winding of the line switch and the following circuit is closed to operate relay H-5; multiple 526, brush 527, conductor 528, right-hand armature and back contact of relay E-5, conductor 529, upper winding 55 of relay H-5, conductor 530, right-hand armature and back contact of relay G-5, conductor 531, conductor 515, armature 516 of relay B-5 to ground. Relay H-5 in attracting its armature 532 locks itself to the grounded sleeve wire 550 and extends 60 this grounded wire 550 over conductor 533, middle right armature and front contact of relay J-5, conductor 534 to the relay K-5. Relay K-5 in attracting its armature 502 disconnects the grounded sleeve wire 70 550 from the control lead 500 leading back to the relay J-4, Fig. 4 of the relay and repeating coil equipment circuit. Relay J-4 in retracting its outer left-hand armature 75 operates relay B-4, Fig. 4 over the following circuit: free pole of battery, relay B-4, outer left armature and back contact of relay J-4, conductor 344, armature 422 and front contact of relay M-4, conductor 403 to ground at the outer left armature and 80 front contact of relay Q-4. Relay B-4 in attracting its outer right armature closes a substitute ground to hold up the slow relay F-5 to prevent ringing from occurring at this time; ground, left-hand armature of 85 relay E-4, conductor 345, outer left armature and back contact of relay F-4, outer right armature and front contact of relay B-4, control conductor 413, contact 431 of 90 relay M-4, brush 433, multiple 434, conductor 435, conductor 500, front contact and armature and lower winding of relay F-5 to free pole of battery. Relay F-5 was energized upon the first impulse to the vertical 95 magnet, this circuit being as follows: free pole of battery, lower winding of relay F-5, lower armature and front contact of slow relay 519, innermost right-hand armature and front contact of relay J-5, conductor 514, conductors 531 and 515 to ground at the upper inner armature and front contact of relay B-5. When energized, relay F-5 is locked 100 by way of its armature 535 and front contact, conductor 501, armature 502 and back contact of relay K-5 to grounded sleeve wire 550. Consequently, the operation of relay K-5 to cause the reversal of direction of the current flow in the loop leading back to the toll operator's position opened the 105 circuit of slow relay F-5 and unless a substitute circuit is provided for holding it up the ringing operation would automatically take place. This is prevented by applying a substitute ground to the control conductor 500 as described over the circuit traced to hold the relay F-5 until the operator, by depressing a key as will be explained, releases it to start the automatic ringing operation. The release of the relay J-4 and the 110 consequent energization of relay B-4 as described reverses the direction of current flow in the talking conductors leading back to the operator's position. After having turned the dial for the last digit, the operator restores her dialing key DK which releases relay E-72 which disconnects the dial from the tip of the plug causing the release of the 115 relay A-2 Fig. 2 and causes the closure of an energizing circuit for the right-hand winding of relay C-2, relay B-43 and re- 120 125 130

lay A—2. Relay A—2 it will be remembered, releases under this condition and in retracting its left armature deenergizes relay I—2, which in releasing causes the release of relay D—2. The polarized relay F—2 is now bridged across the trunk from upper talking conductor 212, Fig. 2, conductor 211, polarized relay F—2, conductor 210, inner right armature and front contact of relay B—2, conductor 209, conductor 208, left-hand winding of relay C—2, armature and front contact of relay C—2, conductor 207, outer left armature and back contact of relay H—2, conductor 206 to lower talking conductor 203. The reversal of the direction of current in the talking conductors due to the operation of relay B—4 causes the relay F—2 to operate closing the following circuit for relay G—2: free pole of battery, relay G—2, conductor 224, contact 225 of relay F—2, conductors 226, 227, 228, inner left armature and front contact of relay B—2 to ground. Relay G—2 locks itself up over the following circuit: free pole of battery, relay G—2, conductor 224, conductor 229, front contact and armature 230 of relay G—2, conductor 231, conductors 227, 228 to ground at the inner left-hand armature of relay B—2. Relay G—2 connects the talking conductors of Fig. 2 through to the talking conductors of Fig. 1 whereupon the trunk and toll supervising relay B—43 operates in series with the relay A—5 Fig. 5 and lights the supervisory lamp 100 as a ringing signal to the toll operator. Relay G—2 Fig. 2 cuts off the bridge including relays C—2 and A—2. It will be noted that when relay D—2 releases, relay H—2 operates over a circuit traceable from free pole of battery, relay H—2, right-hand armature and back contact of relay D—2, inner right-hand armature and front contact of relay E—2, conductors 282 and 228 and the inner left-hand armature and front contact of relay B—2 to ground. The left-hand armature of relay H—2 in opening its back contact, interrupts the bridge including relay F—2 and the left-hand winding of relay C—2. However, due to the operation of relay G—2, the toll supervisory lamp will not flash. Relay C—2, in releasing, introduces another break in the bridge previously traced for polarized relay F—2. The operator now operates her ringing key RK which impresses alternating current upon the talking conductors to operate the alternating current relay A—4 in bridge of the trunk (Fig. 4) which in attracting its armature operates the relay E—4. This relay in attracting its right armature opens the circuit heretofore traced, which has been holding relay F—5, Fig. 5, energized. This relay in retracting its armatures 536, 537, connects ringing current to the called line through its upper winding. This ringing current is continued until the called party

removes his receiver, resulting in an increase in the current through the upper winding of relay F—5 causing the same to operate removing the ringing current. The attraction of the armature 535 of this relay closes a locking circuit for the same over control conductor 500 as traced to ground at the back contact of E—4. The extension of the tip and ring conductors by relay F—5 to the called line operates relay G—4 over the windings of which talking current is fed to the called line. Relay G—4 in operating energizes relay F—4 which in attracting its outer left-hand armature applies ground to the control conductor 413 to hold up relay F—5, Fig. 5 independently of the relay E—4. Relay F—4 in attracting its inner left armature closes a bridge across conductors 446, 409, to hold up relay O—4, and opens the connection of battery through the windings of relay O—4 to the talking conductors leading back to the operator's position which causes the deenergization of supervisory relay B—43. This relay in retracting its armature extinguishes the supervisory lamp 100 which notifies the operator that the subscriber has responded. Talking current is fed to the called line over the windings of relay G—4 and the repeating coil 404. This talking circuit is a standard repeating coil transmission circuit used in long distance connections. Talking current is fed to the calling line from the distant exchange. During conversation the trunk leading from the left-hand windings of repeating coil 404 through the right-hand windings of the repeating coil (not shown) at the distant office is dry, in accordance with standard practice.

The operator now operates her listening key LK and requests the original calling now the called subscriber at the substation shown in Fig. 5 to deposit the necessary coins in the coin box which may be of the type shown in Patent 1,043,219, issued November 5, 1912, to O. F. Forsberg. These coins in passing through the box strike gongs whereby the operator is informed of the denominations of the coins inserted. When she is satisfied that the proper coins have been deposited she presses the collect key 181 which operates relay C—4 thereby applying positive current from the relatively high potential source 447 at the automatic office to the subscriber's line to operate the polarized magnet P in the coin box to collect the deposited coins. The circuit for operating relay C—4 is as follows: free pole of battery 130, key 181, rings of the plug and jack, lower or ring conductors Figs. 2, 3 and 4, lower left-hand winding of repeating coil 404, inner right armature and front contact of relay B—4, left armature and back contact of D—4, relay C—4, conductor 408, to ground at the outer right

- armature and front contact of relay F-4. Relay C-4 in attracting its inner left armature operates relay K-4 which connects the outgoing tip and ring conductors to conductor 448 leading to the source of positive charging current 447. This current flows out over the talking conductors in parallel to ground through the polarized magnet P in the coin box which operates to collect 10 the coins. The relay H-4 operates in this circuit and at its outer right armature and the right armature of relay C-4 applies a distinctive tone from a source 451 to the tip conductor and thence to the operator's head 15 set. This circuit includes the upper or tip conductor Figs. 4, 3, 2 and 1, right normal contact of relay E-72 normal contact of key 180, alternate contact of key E-99, normal contact of keys RK, K', alternate contact 20 of listening key LK, the operator's head set, alternate contact of key LK, normal contacts of keys K', RK to ground at alternate contact of key 181. This tone informs her that the coin circuit is functioning properly. 25 When she releases the collect key the relay C-4 releases, disconnecting the charging current from the line whereupon the polarized magnet restores and opens the contact 538 disconnecting the magnet from the line. 30 She now again presses the key and if the coin box magnet has functioned properly and thus removed the ground, the relay H-4 will fail to operate and she will not hear the collect tone in her head set. If, on 35 the other hand, it has not operated the ground remains connected and the relay H-4 again causes a tone to be transmitted to her head set. If she cannot by repeated closures of the key 181 disconnect the tone 40 she knows the coin box is defective and reports the line out of order.
- Assuming however that the coins are collected she restores her listening key LK and allows the conversation to proceed.
- If the subscriber at station A desires the attention of the operator he moves his switch hook up and down which causes the supervisory lamp 100 at the operator's position to flash, as in usual manual practice, without 45 releasing the switches. This is apparent from the preceding description inasmuch as relay G-4, Fig. 4 is in circuit with the called line and each time it retracts its armature it removes battery and ground from 50 the trunk conductors leading back to the supervisory relay B-43 and puts a bridge including resistance 401 across the relay O-4 to hold it operated.
- If for any reason the deposited coins are 55 to be refunded the operator actuates refund key 180 which operates relay D-4 which applies current of negative polarity from the source 452 at the automatic office to the line to operate the coin box magnet in the 60 other direction to refund the coins. The cir- 65 cuit for relay D-4 leads from the free pole of source 140, key 180, the tip conductor Figs. 1, 2, 3 and 4, upper left-hand winding of repeating coil 404, left armature and front contact of relay B-4, right armature and back contact of relay C-4, relay D-4, inner right armature and front contact of relay F-4 to ground. Relay D-4 operates similar to relay C-4 to cause relay K-4 to connect the outgoing tip and ring conductor to conductor 448 to which is now connected negative current at the outer right armature of relay D-4 from source 452. The coin box magnet operates in this circuit to refund the coins and relay H-4 cooperates with relay D-4 to connect tone of a different character from source 450 to the ring conductor and thence to the operator's head set to inform her that the coin circuit is functioning properly. When she releases key 180 and again depresses it she will hear no tone if the coin box magnet P has operated and removed the ground, and if it has not she will again receive the tone as in the former case.
- The replacement of the receiver by the subscriber does not remove the control of the coins from the operator. If she depresses the collect key after the subscriber has replaced his receiver the circuit for relay C-4 leads to ground through contact 453 of relay F-4, conductor 409, and the right coil of relay O-4 instead of at the outer right armature of relay F-4. This relay releases when relay G-4 in the line circuit releases due to the replacement of the receiver. If the refund key is operated under these circumstances the relay D-4 is operated through the battery connected to the left coil of relay O-4.
- When the called subscriber replaces his receiver the lamp 100 at the toll operator's position Fig. 1 is lighted. The operator may re-ring the subscriber, if she desires to recall him, by actuating her ringing key RK which operates relay A-4 to operate E-4 which in attracting its left-hand armature again releases relay F-5 Fig. 5 which initiates the ringing operation. The control of this relay F-5 was removed from the relay E-4 by the attraction of the outer left armature of relay F-4 when the subscriber responded and was restored to the relay E-4 and consequently to the operator when the subscriber replaced the receiver and de-energized relay F-4.
- When the operator desires to break down the connection after the called subscriber has replaced his receiver, she removes the plug TT from the toll switching jack TSJ. This releases relay O-4 Fig. 4 which causes the restoration of all the switches. If, however, the operator removes the plug while the called subscriber still has his receiver off the switch hook, the switches are not released since relay O-4 which controls the

release is maintained energized over the following circuit: battery, left-hand winding of relay O-4, conductor 400, resistance 401, inner left armature of relay F-4, conductor 409, right winding of relay O-4 to ground at the lower normal contact of switch Y-4, it being noted that the relay F-4 which controls this loop circuit is itself controlled by relay G-4 in circuit with 10 the called line and controlled at the switch hook of said line.

Assuming, however, that the called subscriber has replaced his receiver, when the operator removes the plug, relay O-4 in releasing deenergizes relay Q-4. Relay Q-4 in retracting its inner left armature removes ground from the sleeve conductor 410 leading over the sleeve conductor 380. The removal of this ground releases relay D-3 20 whereupon the release magnet 340 operates as follows: free pole of battery, magnet 340, off normal switch contact 341, right armatures and back contacts of relays B-3 and A-3 to ground at the armature 311 and 25 back contact of relay D-3. Thus the incoming selector is restored and upon reaching its normal position opens the off normal springs 313 and 341. The removal of ground from conductors 403, by the retraction of outer left-hand armature of relay 30 Q-4 releases relay M-4 and the retraction of the right-hand armatures of relay O-4 and right armature of relay Q-4 closes the circuit of the release magnet W-4 of the 35 toll transmission selector as follows: free pole of battery, magnet W-4, lower contact of off normal switch 416, conductor 454, back contact and right hand armature of relay Q-4 to ground at the right-hand armature and back contact of relay O-4.

The relay L-4 is provided to permit the toll operator to apply ringing current to a selected private branch exchange line to signal the operator thereof. This relay is 45 operated when relay E-4 is operated due to the actuation of the ringing key by the toll operator. In private branch exchange working the called subscriber may hang up his receiver, but due to the bridge at the 50 private branch exchange operator's board the relay G-4 remains operated and thus no disconnect signal is given to the toll operator.

What is claimed is:

55 1. In a machine switching system wherein the toll operator sets automatic switches at a distant automatic office over a two-wire interoffice toll trunk and trunks local to the automatic office, and the completed connection includes a repeating coil at the automatic office, the combination with coin boxes at the substations of the lines having coin disposal magnets therein, sources of collect and refund current at the automatic office, 60 electromagnetic means at said automatic office to apply current from one or the other of said sources to selectively operate said magnet to collect or refund coins, and means under the control of the toll operator to control said electromagnetic means over said 70 interoffice trunk and local trunks.

2. In a machine switching system wherein the toll operator sets automatic switches at a distant automatic office over a two-wire interoffice toll trunk and trunks local to the 75 automatic office, and the completed connection includes a repeating coil at the automatic office, the combination with coin boxes at the substations of the lines having coin disposal magnets therein, sources of collect and refund current at the automatic office, electromagnetic means at said automatic office to apply current from one or the other of said sources to operate said magnet to collect or refund coins, and means actuated by the coin current applying means for transmitting a characteristic tone back to the toll operator, and means under the control of the toll operator to control said electromagnetic means over said 80 interoffice trunk and local trunks.

2. In a machine switching system wherein the toll operator sets automatic switches at a distant automatic office over a two-wire interoffice toll trunk and trunks local to the automatic office, and the completed connection includes a repeating coil at the automatic office, the combination with coin boxes at the substations of the lines having coin disposal magnets therein, sources of collect and refund current at the automatic office, electromagnetic means at said automatic office to apply current from one or the other of said sources to operate said magnet to collect or refund coins, and means actuated by the coin current applying means for transmitting a characteristic tone back to the toll operator, and means under the control of the toll operator to control said electromagnetic means over said 85 interoffice trunk and local trunks.

3. In a machine switching telephone system wherein the toll operator sets automatic switches at a distant automatic office over a two-wire interoffice toll trunk and trunks local to the automatic office, and the completed connection includes a repeating coil at the automatic office, the combination of coin boxes at the substations of the lines having coin disposal magnets therein, sources of collect and refund current at the automatic office, a pair of relays at said automatic office, and manual means controlled by the toll operator for operating either of said relays over said interoffice trunks and 95 local trunks to apply current from one or the other of said sources to selectively operate said magnet to collect or refund coins.

4. In a machine switching telephone system wherein the toll operator sets automatic switches at a distant automatic office over a two-wire interoffice toll trunk and trunks local to the automatic office, and the completed connection includes a repeating coil at the automatic office, the combination with coin boxes at the substations of the lines having coin disposal magnets therein, sources of collect and refund current at the automatic office, and means including a pair of relays at said automatic office, one connected in 110 each side of the trunk, a pair of keys controlled by the toll operator for applying current to either side of the completed connection including said interoffice trunk and local trunks to operate the corresponding relay to supply current from the corresponding source to the said magnet to selectively operate the same.

5. In a machine switching telephone system wherein the toll operator sets automatic 115 120 125 130

switches at a distant automatic office over a two-wire interoffice toll trunk and trunks local to the automatic office, and the completed connection includes a repeating coil 5 at the automatic office, the combination of coin boxes at the substations of the lines having coin disposal magnets therein, sources of collect and refund current at the automatic office, a pair of relays at said 10 automatic office, and manual means controlled by the toll operator for operating either of said relays over said interoffice trunks and local trunks to apply current from one or the other of said sources, to selectively operate 15 said magnet to collect or refund coins, and means including a source of current controlled by each relay for transmitting a distinctive tone back to the toll operator.

6. In a machine switching telephone system wherein the toll operator sets automatic switches at a distant automatic office over a two-wire interoffice toll trunk and trunks

local to the automatic office, and the completed connection includes a repeating coil 25 at the automatic office, the combination of coin boxes at the substations of the lines having coin disposal magnets therein, sources of collect and refund current at the automatic office, a pair of relays at said 30 automatic office, manual means controlled by the toll operator for operating either of said relays over said interoffice trunks and local trunks to apply current from one or the other of said sources to selectively operate 35 said magnet to collect or refund coins, a relay in circuit with the said current, and means including a circuit controlled jointly by said relay and the operated coin current applying relay for transmitting a distinctive tone back to the toll operator. 40

In witness whereof, I hereunto subscribe my name this 24th day of February A. D., 1921.

RAY L. STOKELY.
